FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view thereof taken along line "9-9" of FIG. 7, the cross-sectional view in the opposite direction being a mirror image thereof;

FIG. 10 is a lower perspective cutaway view thereof taken along line "9-9" of FIG. 7;

FIG. 11 is a perspective view of a second embodiment of gaming machine archways with overhead display screens showing the new design;

FIG. 12 is a lower perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a cross-sectional view thereof taken along line "19-19" of FIG. 17, the cross-sectional view in the opposite direction being a mirror image thereof; and,

FIG. 20 is a lower perspective cutaway view thereof taken along line "19-19" of FIG. 17 thereof.

In these drawings, the solid lines illustrate the claimed ornamental design, whereas broken lines illustrate unclaimed environmental features and form no part of the claimed design.

The claimed design is shown with a symbolic break in its length in FIGS. 11-20. The appearance of any portion of the article between the break lines forms no part of the claimed design.
